UNITED STATES PATENT OFFICE

158,818

TABLESPOON FOR INFANTS

Louis B. Titensky, Kansas City, Mo.

Application May 16, 1949, Serial No. 2,698

Term of patent 3½ years

(Cl. D44—29)

To all whom it may concern:

Be it known that I, Louis B. Titensky, a citizen of the United States, residing at 4324 Bellefontaine, Kansas City, in the county of Jackson and State of Missouri, have invented a new, original, and ornamental Design for a Tablespoon for Infants, of which the following is a specification, reference being had to the accompanying drawing, forming a part thereof.

Fig. 1 is a perspective view of a tablespoon for infants, showing my new design.

Fig. 2 is a side elevational view thereof; and
Fig. 3 is a plan view thereof.

I claim:

The ornamental design for a tablespoon for infants, as shown.

LOUIS B. TITENSKY.
